UNITED STATES PATENT OFFICE.

GEORGE D. HOLBROOK, OF SEEKONK, MASSACHUSETTS, ASSIGNOR TO
THE DAGGETT & CLAP CO., OF ATTLEBORO, MASSACHUSETTS, A
CORPORATION OF MAINE.

BRACELET.

No. 830,998.

Specification of Letters Patent.

Patented Sept. 11, 1906.

Application filed January 16, 1906. Serial No. 296,297.

To all whom it may concern:

Be it known that I, GEORGE D. HOLBROOK, a citizen of the United States, residing at Seekonk, in the county of Bristol and State of Massachusetts, have invented a new and useful Improvement in Bracelets, of which the following is a specification.

This invention has reference to an improvement in bracelets, and more particularly to an improvement in concealed hinges for bracelets.

The object of my invention is to improve the construction of a concealed hinge for bracelets, whereby the construction of the hinge is simplified and the cost of manufacturing the same reduced.

My invention consists in the peculiar and novel construction of a concealed hinge for bracelets, having details of construction as will be more fully set forth hereinafter.

Figure 1 is a side view of a bracelet provided with my improved concealed hinge and showing the bracelet in the closed position in full lines and in the open position in broken lines. Fig. 2 is an enlarged detail sectional view of the hinge end of the bracelet looking at the outside face of the hinge. Fig. 3 is an enlarged detail sectional view taken on line 3-3 of Fig. 2 and showing the hinge in the closed position. Fig. 4 is an enlarged detail sectional view similar to Fig. 3, showing the hinge in the open position. Fig. 5 is an enlarged detail view looking at the outer face of the solid hinge member, and Fig. 6 is an enlarged detail view looking at the outer face of the tubular hinge member.

In the drawings, *a* indicates one semi-oval half, *b* the opposite semi-oval half, and *c* the improved concealed hinge, of the bracelet.

The semi-oval halves *a* and *b* are constructed from a tube which is oval in cross-section. The half *a* has the open end *a'* for the hinge *c* and the end *a''*. The half *b* has the open end *b'* for the hinge *c* and the end *b''*. The ends *a'* and *b'* and the ends *a''* and *b''* coincide when the bracelet is closed. The ends *a''* and *b''* may be provided with any one of the well-known forms of catches adapted to hold the ends together when the bracelet is closed.

My improved concealed hinge *c* consists of a solid member *d* and a tubular member *e*. These members *d* and *e* are curved to conform to the contour of the bracelet and shaped

to fit in the open ends *a'* and *b'* of the bracelet. The member *d* is constructed to have a solid body portion *d'*, from one end of which extends the side arms *d''* *d''*, forming a central opening *d''*, and having the oppositely-disposed semicircular notches *d''* *d''* in their outer edges, as shown in Fig. 5. The tubular member *e* is formed from thick sheet metal and shaped to have the tubular body *e'*, from the inner face of which at one end extends the central arm *e''*, merging into the T-shaped end *e''*, which forms the pintle of the hinge, as shown in Figs. 3 and 6. The width of the arm *e''* coincides with the width of the opening *d''* in the member *d*, and it is curved outwardly to bring the T-shaped end into the notches *d''* *d''*, as shown in Figs. 2 and 3. 70

The hinge is assembled by placing the arm *e''* of the member *e* in the opening *d''* in the member *d* with the T-shaped end *e''* in the notches *d''* *d''*, as shown in Fig. 2. The members *d* and *e* of the hinge are now forced into the open ends *a'* and *b'* of the bracelet into a position to bring the end of the member *e* (adjacent the arm *e''*) inside the end *b'* of the bracelet, thus forming a shallow recess *e''* in the end *b'*, and the T-shaped end *e''* against the inner face of the outer portion of the end *a'* of the bracelet, thereby locking the T-shaped end *e''* in the notches *d''* *d''*, as shown in Fig. 3. The body portions *d'* and *e'* of the hinge members are now secured in the ends *a'* and *b'* of the bracelet by solder or other means.

When the bracelet is opened, the member *d* of the hinge in the end *a'* of the bracelet pivots on the T-shaped end *e''* of the member *e* 90 and the outer edge of the end *a'* of the bracelet swings into the recess *e''* and against the concaved face of the arm *e''*, as shown in Fig. 4.

By the use of my improved construction I provide a bracelet with a strong and durable 95 concealed hinge having only two members, each of which is formed integral.

Having thus described my invention, I claim as new and desire to secure by Letters Patent—

1. A concealed hinge-joint for bracelets, comprising two members each of integral formation, one embodying a body portion formed with a pair of forwardly-projecting arms having a space between said arms throughout 105 the entire area thereof, and with a notch on

the top edge of each of the arms, the other member embodying a body portion formed with a central curved integral T-shaped arm on its outer end, said arm projecting upwardly between said first-named pair of arms and having the head thereof engaging in said notches of said arms.

2. A concealed hinge-joint for bracelets, comprising two integral members each having a body portion, one being formed with a pair of forwardly-projecting spaced arms, said arms having a notch formed on their top edges, the second body portion being formed with a forwardly-projecting central curved

T-shaped arm on its outer end which merges 15 into said second body portion at a point adjacent the bottom thereof, said curved arm extending upwardly in said space between said pair of arms and having its T-shaped head extending in said notches of said pair of 20 arms.

In testimony whereof I have signed my name to this specification in the presence of two subscribing witnesses.

GEORGE D. HOLBROOK.
